AGITATOR FOR WASHING MACHINES

Jabez Curry Nelson, Syracuse, N. Y., assignor to
 Easy Washing Machine Corporation, Syracuse,
 N. Y., a corporation of Delaware

Application December 23, 1935, Serial No. 55,716

8 Claims. (Cl. 259—101)

My invention relates to washing machines and more particularly, to a novel agitator or dolly therefor.

An object of my invention is to provide an agitator adapted to be mounted in a washing vat for oscillation therein which is adapted to cleanse the clothes thoroughly and in a minimum length of time.

Another object of my invention is to provide an agitator for a washing machine adapted to be oscillated in a washing vat, the agitator having a central irregularly shaped body portion and blades so constructed and arranged that they cooperate with the body portion to cause a turbulence of the washing fluid, a thorough intermingling of the clothes and washing fluid and a constant circulation thereof, whereby new clothes surfaces are constantly being presented to the action of the agitator.

More specifically, my invention contemplates the provision of an agitator for a washing machine in which the central body portion of the agitator comprises two pyramidal shaped figures placed base to base, with the bases inclined to the horizontal, whereby an irregularly shaped body portion is formed and in which a plurality of blades are provided adapted to cooperate with the body portion to produce a turbulence of the washing fluid and a substantial thread-deforming action on the clothes, whereby the clothes are thoroughly cleansed.

Other objects and advantages of my invention will be more apparent from the following description when taken in connection with the accompanying drawing, in which:

Figure 1 is a view of the invention showing my novel agitator and indicating the vat in which it is operated.

Figure 2 is a view taken on the line 2—2 of Figure 1.

Figure 3 is a view taken on the line 3—3 of Figure 1.

The agitator of my invention is adapted to be mounted in a vat or tub 11 in which the clothes and washing fluid are placed. The washing vat may be of any desired shape, either square or, as shown in the drawing, circular in cross section. The agitator, generally indicated by the numeral 12, is preferably mounted centrally of the vat 11 and is driven by a shaft 13 extending upward through the bottom of the vat. Suitable means are provided for supporting the agitator and enabling it to be driven by the shaft 13, such means including a sleeve 14 which extends upward through the bottom of the vat

concentric with the shaft 13. The preferred manner of supporting and driving the agitator is more particularly shown and described in a co-pending application of Peter Eduard Geldhof filed December 18th, 1935, Ser. No. 55,050. The 5 drive shaft 13 may be driven by any suitable mechanism and from any suitable source of power, not necessary to be shown or described herein since such driving mechanism is well known in the art to which this invention applies. 10 Preferably, the shaft is driven in an oscillatory manner so as to drive the agitator through an arc of 180 degrees, more or less, and at a speed of between fifty and sixty oscillations per minute.

The agitator 12 comprises a base 16 which is 15 mounted close to the bottom of the vat 11 and is sloped slightly upward from the outer circumference toward the center thereof. The body portion of the agitator comprises an irregularly shaped figure which is made up of two substantially pyramidal shaped structures 17 and 18 mounted with their bases 19 and 21 in the same plane. It has been found that a better washing 20 action is secured if the body portion is mounted so that the bases 19 and 21 of the pyramids lie 25 in a plane at an angle to the horizontal, whereby the body portion presents an unsymmetrically shaped structure to the clothes.

The apices of the pyramids 17 and 18 are cut off on substantially horizontal planes so that the 30 pyramids are actually frusto-pyramidal with the lower triangularly shaped cut off portion 22 resting upon the base 16 and the upper substantially triangularly shaped cut off portion 23 presenting a horizontal plane for the reception 35 of a cap 24 which may be mounted on the top of the agitator in any suitable manner. The cap 24 may be of any desired shape and is provided with a lower flat surface 26 adapted to prevent the upward splashing of cleansing fluid when the 40 agitator is oscillated.

The left hand side of each face of each of the pyramids is extended beyond the plane of the adjacent face to form blades 27, 28 and 29, that is, for example, the surface 31 of the upper pyramid and the surface 32 of the lower pyramid are extended to the left beyond the plane of the adjacent faces 33 and 34 to form blade 28. The blades, toward their outer edges, are slightly curved in a clockwise direction as more clearly shown in Figure 3, whereby to form a shallow pocket extending lengthwise of each of the blades. The outer edges 36 of the blades are rounded off, as more clearly shown in Figures 2 and 3, so as to prevent the formation of sharp 55

edges which would be likely to tear the clothes. The blades, further, are comparatively narrow at the top of the agitator, for example, as at 37, and gradually increase in width toward the corners 38 of the upper pyramid where they are appreciably wider. The blades beyond the corner 38 of the pyramid are narrowed somewhat and extend downward substantially in the plane of the adjacent face of the agitator with the outer ends slightly curved in a horizontal plane in a clockwise direction. Near the base 16, as at 39, the outer edges 36 of the blades are curved outward so that the lower edges of the blades extend substantially to the periphery of the base 16.

Extending downward on the faces of the upper pyramid 18 from the lower surface 26 of the cap to the base 19, are a plurality of small blades 41, 42 and 43. Each of these blades, at the top, extends to the outer periphery of the cap 24 and gradually becomes narrower toward the base 19 substantially in conformity with the slope of the faces of the pyramid. Although each of these blades may be made radial or may be inclined in a clockwise direction with respect to a normal to the corresponding face, preferably, the blade 41 extends radially while the blades 42 and 43 are inclined from a normal to the plane of the face of the pyramid in a clockwise direction.

When the agitator is oscillated, the clothes and washing fluid are carried backward and forward in accordance with the oscillations of the agitator. Due to the fact that the agitator is not symmetrical, a turbulent, forceful, action occurs which is substantially equally effective throughout the depth of the cleansing fluid. The blades 41, 42 and 43 effect a substantial scrubbing thread-deforming action on the clothes. The blades 27, 28 and 29, because of pockets formed on the clockwise sides of the blades, tend to cause the clothes and washing fluid to circulate in the clockwise direction. The resultant clockwise rotation of the clothes and washing fluid occurs because the blades 27, 28 and 29 exert a more powerful thrust on the clothes and washing fluid when the agitator is rotated in the clockwise direction than when rotated in the counter-clockwise direction so that the clothes are periodically caused to change their relative positions in the vat so that new clothes surfaces are constantly being presented to the action of the agitator.

While I have shown the preferred form of my invention, it will be apparent that various modifications and changes may be made in the form of the agitator and relation of parts thereof without departing from the spirit of the appended claims.

I claim:

1. An agitator adapted to be mounted for oscillation in a vat containing clothes and washing fluid, said agitator comprising two pyramidal shaped figures having their bases facing upon each other and constituting a body portion for the agitator, said bases extending at an angle to the horizontal, and a plurality of blades extending from said body portion.

2. An agitator adapted to be mounted for oscillation in a vat containing clothes and washing fluid, said agitator comprising two pyramidal shaped figures having their bases facing upon each other and constituting a body portion for the agitator, said bases extending at an angle to the horizontal, and a plurality of blades extending from said body portion, said blades being formed by extending each face of the pyramid along one

side thereof beyond the plane of the adjacent face.

3. An agitator adapted to be mounted for oscillation in a vat containing clothes and washing fluid, said agitator comprising two separate and distinct pyramidal shaped figures mounted substantially one above the other and constituting a body portion for the agitator, a base toward which the apex of the lower of said two pyramidal shaped figures extends, and a plurality of blades extending from said body portion.

4. An agitator adapted to be mounted for oscillation in a vat containing clothes and washing fluid, said agitator comprising two pyramidal shaped figures having their bases facing upon each other and constituting a body portion for the agitator, and a plurality of blades extending from said body portion, each of said blades being curved in the same direction in horizontal cross section.

5. An agitator adapted to be mounted in a vat containing clothes and washing fluid, said agitator comprising two pyramidal shaped figures constituting a body portion for the agitator, and a plurality of blades formed by extending each face of the two pyramids along one side beyond the plane of the adjacent face, each of said blades being curved in the same direction in horizontal cross section.

6. An agitator adapted to be mounted for oscillation in a vat containing clothes and washing fluid, the agitator being in over-all diameter less than half the diameter of the vat so as to provide a space surrounding the agitator for receiving and washing clothes, said agitator comprising two separate and distinct substantially pyramidal shaped figures mounted substantially one above the other and constituting a body portion for the agitator, the apex of the lower of said pyramids extending downward toward the bottom of the vat and the apex of the other pyramid extending upward toward the surface level of the liquid in the vat.

7. An agitator adapted to be mounted for oscillation in a vat containing clothes and washing fluid, the agitator being in over-all diameter less than half the diameter of the vat so as to provide a space surrounding the agitator for receiving and washing clothes, said agitator comprising two separate and distinct substantially pyramidal shaped figures mounted substantially one above the other with their bases facing upon each other and constituting a body portion for the agitator, and a plurality of blades extending from said body portion, said blades being formed by extending the faces of the pyramids beyond the plane of the adjacent faces.

8. An agitator adapted to be mounted for oscillation in a vat containing clothes and washing fluid, the agitator being in over-all diameter less than half the diameter of the vat so as to provide a space surrounding the agitator for receiving and washing clothes, said agitator comprising a substantially disc-shaped base and two separate and distinct substantially pyramidal shaped figures constituting a body portion extending upward from said disc-shaped base, said pyramidal shaped figures being mounted with their bases contiguous and with the apex of one of the pyramids extending downward toward said disc-shaped base and the apex of the other pyramid extending upward toward the surface level of cleansing fluid.

JABEZ CURRY NELSON.
